GLASS WORKING MACHINE

David E. Gray, Corning, N. Y., assignor to Corning
Glass Works, Corning, N. Y., a corporation of
New York

Application October 4, 1939, Serial No. 297,943

5 Claims. (Cl. 49—5)

The present invention relates to a glass working machine of the single mold type which gathers charges of glass from a molten supply body and fabricates them into ware.

One object of the invention is a simple method of gathering charges of glass and of their fabrication into ware.

Another object is a glass working machine which is readily adaptable for the fabrication of a wide variety of forms and sizes of blown ware.

A further object is a machine for the automatic gathering and fabrication of glass charges into ware in which the speed of operation and the timing of the various functions can be readily modified during the operation of the machine.

The invention embodies among its features a glass working machine of the single mold type having a combined gathering, shearing, and blow-head assembly adapted to gather a charge of glass from the surface of a molten supply body, shear the charge therefrom, prepare the charge for introduction into a finishing mold while conveying the charge thereto, and to eject the finished article from such assembly in the course of its movement toward the molten supply body for a subsequent charge.

A further feature of the invention is the simplification of mechanical structure by resorting to the use of electrically actuated controlling solenoids and a plurality of electric motors rather than complex mechanical controls and a single power source.

A still further feature embodies the employment of a novel form of timer by means of which the timing of occurrence of an entire group of functions may be modified as a whole with respect to other functions, or may be individually modified with respect to one another to suit best operating performance.

Other features of the invention will appear as the specification progresses.

A preferred form of machine embodying the invention is illustrated in the accompanying drawings wherein

Fig. 1 is a plan view of the machine;

Fig. 2 is a side elevation of Fig. 1;

Fig. 2a is a fragmentary view in elevation and partly in section illustrating a part of a spindle drive mechanism;

Fig. 2b is an enlarged view, partly in section, of a detail of the machine.

Figs. 3 and 4 together show an enlarged side elevation partly in section of the gathering head assembly of the machine;

Fig. 3a is a sectional view of a switch carried by the head assembly;

Fig. 3b is a perspective view of part of the structure illustrated in Fig. 3a;

Fig. 3c illustrates part of the apparatus of Fig. 3 in an alternative position;

Fig. 4a is an elevational view of a fragment of Fig. 4 as seen from the opposite side of the structure;

Fig. 4b is a fragment of the lower end of the structure of Fig. 4, but in an alternative position;

Fig. 4c is a view taken on line 4c—4c of Fig. 4a;

Fig. 4d is a view, partly in section, of a fragment of the machine.

Figs. 5 and 6 are enlarged end and side elevations of fragments of the machine illustrating the head raising and lowering unit;

Fig. 5a is a view taken on line 5a—5a of Fig. 5;

Fig. 5b is a view similar to 5a, but showing the parts in a position they attain while in operation;

Fig. 7 is a plan view of the mold supporting and operating assembly;

Fig. 8 is a side elevational view of the mold supporting and operating assembly showing fragments of the mold halves mounted thereon;

Fig. 9 is a plan view of the mold support assembly showing molds mounted thereon and the arrangement for cooling the mold halves and parison;

Fig. 9a is a detail of the mold cooling nozzle;

Fig. 9b is a fragmentary detail showing part of the linkage between the mold cooling nozzle and the turning post assembly;

Figs. 10 and 11 are enlarged plan and side elevational views of fragments of the mold operating mechanism;

Fig. 12 is an enlarged fragmentary view similar to that of the head assembly shown in Fig. 2, but illustrating a modified form of shear operating mechanism;

Fig. 13 is a detail of the shear operating mechanism of Fig. 12;

Figs. 14 and 15 are details of the head mechanism;

Fig. 16 is a sectional plan view illustrating the quadrant and associated parts;

Fig. 16a is a side elevation partly in section of a fragment of the apparatus disclosed in Fig. 16;

Fig. 17 is a side elevation of Fig. 16;

Figs. 18 and 19 are enlarged plan and side views of the swing mechanism;

Figs. 20 and 20a—20k diagrammatically illustrate the gathering of a charge and its development into finished ware;

Fig. 21 is a schematic wiring diagram of the machine;

Fig. 22 is an end elevation of the timing mechanism;

Fig. 23 is a front view of the timing mechanism partly in section;

Fig. 24 is a plan view of the timing mechanism with its cover removed;

Fig. 24a is a fragmentary view taken on line 24a—24a of Fig. 24; and

Figs. 25 and 26 are sectional side elevations of switches operated by the timing mechanism.

General description

With a view to making the later detailed description clearer, the particular embodiment of the invention shown herein and its manner of operation will first be described generally.

The machine is divided into four major separately powered operating units comprising a gathering head assembly generally designated 13 (Fig. 2), a turning post assembly generally designated 14, a mold operating assembly generally designated 15, and a timing mechanism generally designated 16. These units are mounted on a carriage 11 (Figs. 1 and 2) equipped with jack screws 12 to enable ready leveling of the machine and appropriate adjustment of its height to take care of variation in height of the gathering bowls of different glass melting furnaces with which the machine is likely to be employed.

The motors 33, 34 and 38 of the several units are of the constant speed type and rotate continuously while the machine is in operation. The timing mechanism contains a number of circuit control switches and is continuously operated by its motor 33 through a variable speed transmission 558, whereas the other units are connected to their motors by mechanical linkages under control of solenoids. These solenoids and others hereinafter described are included in circuits under control of switches of the timing mechanism or switches actuated consequent to a movement of the turning post or gathering head assembly, as will readily appear from an inspection of a circuit diagram comprising Fig. 21 of the accompanying drawings.

The gathering head assembly 13 is suspended in a vertical position from a bracket 28 extending laterally from the turning post assembly and is so arranged that an associated head raising and lowering mechanism 31 can move the gathering head assembly vertically. The head assembly (Figs. 2, 3 and 4) is equipped with a gathering cup 40 which is momentarily lowered into a supply body of molten glass (not shown) to gather a charge by suction to form a blank or parison. The parison is sheared from the supply body by a shear blade 150 as the cup is being raised from the supply body by mechanism 31. Instantly following the shearing operation, chuck jaws 61 (Figs. 4-4c) are closed about the gathering cup, the shear operating mechanism is disabled and a plunger 165 (Fig. 4) within the gathering cup 40 is lowered therein and functions to assist the chuck jaws in holding the peripheral edges of the plastic parison attached to the cup. The plunger also functions to expel the central portion of the charge from the cup thereby forming a cavity in the charge. The gathered charge is held at the gathering station for a short time period to allow the heat from the glass supply body to heal the shear mark on the gather after which the gathering head assembly is moved, under control of the timing mechanism, from the gathering position to a position over mold operating assembly 15 by a swing mechanism comprising a part of the turning post assembly 14 and driven by a gear reduction unit including the motor 34. At the beginning of the travel of the gathering head toward the mold operating assembly puff air is supplied through the cup to assist gravitational action in imparting a hollow form to the parison.

As the gathering head is positioned over the mold assembly, it is rotated about its own axis through a drive established between it and a shaft of the gear reduction unit of the turning post drive motor 34. The parison elongates at this time and while elongating, cooling air is directed toward the upper part thereof from nozzles 343 (Fig. 9) as required to properly set up and further assist in the distribution of the glass. After the head has rotated the parison for the time required to obtain proper elongation thereof, the mold closing operation is effected by a mechanism associated with the mold operating assembly 15 actuated by motor 38 (Fig. 2) under the control of the timing mechanism 16. Upon closure of the mold about the blank, low pressure blow air is supplied thereto through the gathering head assembly. After the blowing operation has continued for the necessary time period, the timing mechanism 16 functions to simultaneously cause the mold operating mechanism to open the mold and to vent the finished article to atmosphere. As the mold starts to open, the supply of blow air to the gathering head is also cut off. At substantially the same time, the timing mechanism renders the turning post mechanism effective to return the gathering head assembly to the gathering station. During such return movement, the head raising and lowering mechanism again functions, at which time the movement is utilized to raise the plunger 165 and open the chuck jaws 61 to effect release of the finished article from the gathering head. As such release is effected the chuck jaws are locked in their open position and the shear mechanism is again conditioned for operation following the gathering operation which occurs upon arrival of the gathering head at the gathering station.

Gathering head assembly

Specifically, the gathering head assembly includes a sleeve 21 (Fig. 3) pivotally suspended at 22 and 23 (Fig. 2) from a lever 24 and a rocker arm 25 respectively, which are in turn pivotally supported at 26 and 27 from a bracket 28 fixed to a rotatable post 29 of the turning post assembly. The left hand end of rocker arm 25 is pivotally connected to a connecting rod 239 constituting a part of the gathering head elevating and lowering mechanism which, as heretofore brought out, is actuated by the head raising and lowering mechanism 31. The driving linkage between arm 239 and mechanism 31, hereinafter described in detail, is established at the proper times by a solenoid 32 under the influence of the timing mechanism 16, as will be described later. Passing through the sleeve 21 of the gathering head assembly is a spindle 35 (Figs. 3 and 4). This spindle at its lower end carries the gathering cup 40 which is held in place by a retainer 41 and at its upper end carries a pulley 42 by means of which the spindle and cup are rotated at a time and in a manner to be described later.

A collar 45 is located on the spindle 35 immediately below pulley 42 and at its upper end has integral therewith a pair of radially projecting arms carrying posts 30 adapted to engage a plunger lifting plate 43 secured to the under side of a plunger rod carrying hub 170. This hub is attached to an associated retainer ring 173 and ball bearing suspended from one end of a plunger lowering lever 174 by a link 175. Lever 174 is pivotally mounted at a point intermediate its ends to a bracket 176 attached to sleeve 21 and at its other end is coupled to the armature 177 of

a plunger lowering solenoid 178. Although the position of parts as shown in Figs. 2 and 3 are such that plunger lifting plate 43 is in engagement with posts 30, such posts are not depended upon to hold the plate in such position. The plate is held against being lowered by the action of gravity by introducing friction to its movement through the medium of an associated adjusting screw 39 (Figs. 2 and 2b). In other words, posts 30 merely function to lift plate 43 from a down position to which it has been previously moved by the energization of solenoid 178.

The collar 45 at its lower end carries a chuck operating yoke 58 held thereon by a nut 57, and has trunnion block supporting pins 46 and 46' cast integral therewith which fit into blocks 50 carried in the forked end of a collar supporting lever 51 (Fig. 2) the other end of which is pivotally secured to rocker arm 25 at 52.

The yoke 58 carries lifting rods 60 and 61 which run down alongside sleeve 21 and are threaded into a chuck raising shell bearing collar 62 (Fig. 4) carrying a chuck operating shell 63 through a ball bearing assembly 64. The shell 63 contains a relatively heavy member 65 having chuck supports 66 pivoted thereto equipped with chuck jaws 67 and having free ends 68 extending into slots 69 of shell 63. The member 65 also contains chuck lifting levers 72. Each of these levers has one end 72' extending into a slot 63' in the wall of shell 63 and a forked end 72" straddling a chuck support near its pivot point. These levers have lower surfaces 75 which, as will be more fully brought out later, fulcrum on a plate 76 arranged immediately above the gathering cup 40 to slightly raise the chucks into engagement with the under edge surfaces of the cup after the closure of the chuck jaws thereabout. With the chuck jaws 67 in their open position the member 65 rests on jaw ends 68 which in turn rest on the bottom of the slots 69 in shell 63. As will be made clear later, with the jaws 67 in closed position member 65 rests on its levers 72 which are then supported on plate 76 which is attached to spindle 35.

As previously stated, rocker arm 25 lowers and raises the head assembly to effect ejection of a finished article therefrom immediately after the initiation of the swing movement of the head assembly toward the gathering station. At such time, as the head assembly is being lowered, a bumper 54 (Figs. 2 and 12) secured to bracket 28 limits the downward movement of lever 51 so that movement of member 65 and cup carrying spindle 35 relative to the shell 63 occurs following the engagement of lever 51 with bumper 54. The chuck jaws 67 continue to move downward with member 65 until the free ends 68 of their supports 66 encounter the lower surfaces of slots 69 of the now stationary shell 63 after which the supports are forced to rotate about their pivots thereby opening the chuck jaws. As the chuck jaws reach their full open position their downward movement is arrested by the wedging of their support ends 68 between the lower edges of slots 69 and member 65. This is arranged to occur some time prior to the completion of the downward movement of the cup 40 so that such cup projects downward substantially beyond the bottom of the chuck jaws before its downward movement has been completed. The jaws become locked in their open position by a latch 55 (Figs. 3 and 3c) carried by bracket 176 and moved under the yoke 58 by a spring 56 as the sleeve 21 approaches its lowermost position with respect to the yoke. Dur-

ing the latter portion of the downward movement of sleeve 21, the plunger lifting plate 43 encounters posts 30 so that as the downward movement of the sleeve and of the cup 40 are being completed the plunger is being retracted into the cup. During the raising movement of the head assembly, lever 51 is lifted clear of bumper 54 at which time a latch operating screw 53 carried by an arm 51' depending from lever 51 moves away from a spring actuated latch 106 to connect an associated shear operating rack 103 in relation for operation with a guide 101 carried by the rocker arm 25.

As the gathering head arrives at the gathering station, rocker arm 25 again functions to momentarily lower the sleeve 21 and spindle 35, this time for the purpose of introducing the gathering cup into a supply body of molten glass to gather a charge and also to operate the shear mechanism, as will hereinafter appear.

A gather is obtained by suction during the momentary contact of the cup with the glass in a manner hereinafter described. During the raising of the assembly and separation of the charge from the supply body by the shear 150, latch 55 is tripped in a manner to be described later, thereby allowing the downward movement of the shell 63 with respect to the gathering cup 40. As shell 63 is lowered with respect to the gathering cup, the chuck jaws 67 are moved toward their closed position by the engagement of the bottom of shell 63 with slanting surfaces 70 of supports 66. The lowering of shell 63 permits member 65 to lower the chuck jaws with respect to cup 40 so that they can close about the cup in the position illustrated in Fig. 4b. Just before the shell 63 has reached its limit of downward travel, the surfaces 75 of levers 72 encounter plate 76 which serves as a fulcrum for these levers and effects a slight lifting movement of the closed chuck jaws into engagement with the bottom surface of the gathering cup 40, as illustrated in Fig. 4c.

Shear operating mechanisms

Alternative forms of shear operating mechanisms are illustrated. Each includes a rack guide assembly 101 (Figs. 2 and 12) pivotally connected at 102 to the rocker arm 25 and containing a rack 103. At the time the head assembly arrives at the gathering station rack 103 is locked in fixed relation to its guide assembly by its latch 106 so that the rack is raised and lowered with arm 25 and transmits rotary motion to a shear driving pinion 108 carried on the free end of bracket 28. This pinion is adapted to in turn drive a rack 110 pivotally connected to a lever 111. This lever at its left hand end is pivoted at 113 (Fig. 2) to bracket 28 and at the other end is forked to accommodate a trunnion block 114 carrying a rack 115. The latter rack operates in a guide 117 secured to the sleeve 21 and is in mesh with a pinion 118. This pinion is integral with a single tooth ratchet disc 120 adapted to drive its supporting shaft 121 during the downward movement of rack 115 through a pawl 122 carried by an arm 123 keyed to such shaft.

In that form of shear operating mechanism illustrated in Figs. 2 and 3 the other end of shaft 121 carries a bevel pinion 124 which is in mesh with a bevel gear 125 keyed to a shear operating shaft 126. The arrangement is such that as rack 115 moves down shaft 121 is turned one complete revolution and through the bevel gear and pinions rotates the shear shaft 126 one complete revolution.

In that form of shear operating mechanism illustrated in Figs. 12 and 13 the other end of shaft 121 carries a crank 128 equipped with a roller operable in a slot 129 of a bracket fixed to a rack 130 operable in a suitable guide 131. This rack is in mesh with a pinion 135 carried upon shear operating shaft 126. The arrangement is such that one revolution of shaft 121 is effective to rotate the shear far enough to shear the glass and to then return the shear to its initial position rather than by continuing its rotation in the same direction to such position. Although this form of structure is slightly more complicated than that employing bevel gears, it is preferable as it is less likely to distort the charge.

In both forms of structure the lower end of the shear operating shaft 126 has keyed thereto a flange 136 (Figs. 4 and 12) to which is secured a shear cam roller operating jaw 137, which on being rotated transmits rotary motion to a sleeve 138 keyed to a shear carrying shaft 139 through a roller 140 carried by an arm 141 integral with sleeve 138. Sleeve 138 is movable endwise of shaft 139 between a collar 164 pinned to the shaft and a spring cup 152 also pinned to the shaft. Adjusting and locking nuts 154 are employed to closely restrict the allowable endwise movement of sleeve 138 relative to shaft 139. A spring 153 within cup 152 normally holds the shaft 139 up relative to sleeve 138. A second arm 142 integral with sleeve 138 carries a roller which runs in the track 144 of a drum cam 145 (Fig. 4) adjustably held in a half cup support 59 (Fig. 2) by cap screws 18 and height adjusting screws 151 (Fig. 4). The support 59 is rigidly mounted on sleeve 21. The contour of track 144 is such that sufficient axial movement is imparted to the shear shaft 139 upon rotation thereof to bring the shear blade 150, on the lower end of this shaft, from a position of rest well above the bottom of the cup 40 to a position slightly below the bottom or shearing face of the cup until the blade is rotated a very slight extent under the face of the cup, after which the blade 150 is resiliently held against the shearing face of the cup while passing thereunder by spring 153, so that it will clearly shear the charges of glass from the parent body as the blade passes under the cup. During the axial movement of shaft 139 its upper end simply variably telescopes into the lower end of hollow shaft 126, the telescoping ends of these shafts acting as bearings for one another.

It has heretofore been mentioned that the chuck collar latch 55 (Figs. 3 and 3c) is tripped by the shear mechanism to close the chuck jaws. This tripping action is effected by a tripping lever 155 pivoted on a bolt 156 passing through bracket 178, and operated immediately following the shearing operation through a lever 158 and a connecting link 159 by a pin 160 carried by bevel gear 124 (Fig. 3) or in the alternative mechanism by a pin carried by a disc 161 (Fig. 12) on shaft 121 of the shear driving mechanism.

It is to be noted also that latch trip screw 53 carried by the depending extension 51' of arm 51 at this time encounters and moves latch 108 clear of the shear operating rack 103 so that on the subsequent lowering and raising cycle of the head assembly to eject a finished article the shear mechanism does not operate.

The plunger 165, arranged within the gathering cup 40 (Fig. 4) and which, as previously stated, functions to assist the chuck jaws in holding the plastic glass attached to the gathering cup, slides between the inner wall of cup 40 and

the outer surface of a retainer 41. The plunger is held against rotary movement relative to cup 40 by a screw 166 passing through the wall of the cup into a vertical groove in the plunger and is movable endwise with respect to cup 40 by a key 167 attached to the lower end of a plunger rod 168 by a nut 169. Plunger rod 168 runs through the center and out of the top of spindle 35 and at its top end (Fig. 3) is secured to the hub 170 of the heretofore described plunger lowering mechanism including the plunger lowering solenoid 178 whose circuit is completed by a switch 180 tripped to closed position, as the chuck jaws close about the gathering cup 40, by a pin 182 projecting from the clutch collar trunnion pin 46'. The contacts of the switch 180 are normally held open against spring tension by a pin 180' (Fig. 3b) operating in a cam slot in a disc 184 of the assembly. As the disc is rotated by the lowering of pin 182 the holding open of such contacts is transferred to a latch 183 until such pin has been lowered enough to trip the latch by engagement with the tail 183' thereof, whereupon closure of the contacts is permitted.

Valve system

It has been heretofore stated that the charge of glass is gathered by suction and afterwards sheared from the parent supply body and mechanically held attached to the gathering cup while being elongated and blown to final form. The suction gathering and blank blowing operations are controlled by atmosphere and puff and blow valves 185 and 187, best illustrated in Figs. 3 and 4, and a vacuum valve of similar construction, not shown, but the stem 185 of which appears in Fig. 15.

The foregoing mentioned valves are mounted in a valve housing 190 which is secured to the side of the sleeve 21. This housing is provided with ports 191 connected to a manifold 192 in line with a hole 193 through sleeve 21. Hole 193 is in line with a manifold formed by a spool 35' comprising a part of spindle 35. An aperture 194 through the wall of spindle 35 enables the passage of air down through the spindle into the cup 40. Packing rings 195 and 196 cooperative with spool 35' prevent air leakage. The top ring 195 is held in place by a tubular weight 198 and the bottom one by a tubular member 199 and a spring 200 held in place by a bushing 201. The puff and blow valve is connected to an air supply line 204 (Fig. 2) by means of a flexible tube 206, and the vacuum valve is in a similar fashion connected to a vacuum supply line 205 by a flexible tube 207, whereas the atmosphere valve 186 is directly connected to atmosphere at 208 (Fig. 3) via the bore of its stem 186'. The vacuum supply line 205 (Fig. 2) is simply connected to a suitable vacuum pump (not shown). The air supply line 204, however, terminates in a two-way valve 201 (Figs. 16 and 17) operable to establish communication between line 204 and a puff air supply line 214 during such time that valve 201 is actuated under control of puff control cams to be described later and to establish communication between line 204 and a blow air supply line 209 during the time the gathering head is over the mold at which time valve 201 is under control of a blow switch 189 (Fig. 7) actuated as the mold is closed about the parison. The vacuum valve is mechanically opened by a lever 157 (Fig. 15) which is pivotally secured to the bracket 178 by bolt 158 and has its free end 157'

forked to accommodate a trunnion block 210 carried by the stem 185 of the vacuum valve. The lever 157 is raised, to actuate the vacuum valve to connect the vacuum line 205 (Fig. 2) in communication with the gathering cup 40, by a lug 211 (Fig. 15) secured to rack 115 of the shear driving mechanism and in such position thereon that the lever 157 is operated near the end of the up stroke of this rack, which occurs as the cup 40 is being lowered into the supply body of glass. The vacuum valve is thereafter held in the open position independently of lug 211 by latch 215 (Figs. 14 and 15) mounted on a bracket 216 and rotated by a spring 217 under an edge of trunnion block 210 as it comes up. An arm 218 of latch 215 is in the path of movement of a pin 219 in fixed relation with the armature 221 of the atmosphere valve solenoid 222 which, upon energization, opens the atmosphere valve 186 and through the medium of pin 219 trips latch 215, allowing the vacuum valve to close. Energization of solenoid 222 is under the joint control of a switch 504 of the timing mechanism 16 (Fig. 24) and a switch 231 (Fig. 4a) and is arranged to occur just after the chuck jaws have closed about the gathering cup 40 and before the plunger solenoid 178 starts lowering the plunger 165. This is accomplished by so setting the actuating member 232 of switch 231 on rod 61 that switch 231 closes its contacts slightly before those of switch 180, which close the circuit of solenoid 178, are closed.

The puff and blow valve 187 (Fig. 4) is normally kept closed by a spring 224 (Fig. 3) and has its stem 187' connected with the armature 225 of a solenoid 226 alternately under control of puff switch 188 (Fig. 17) and blow switch 189 (Figs. 7 and 8) mechanically actuated at the proper times to supply puff and blow air to the parison, as will be more fully described herein-after. To provide for close adjustment of valve 187, it is provided with a thumb screw 228 (Fig. 3) having a right and left hand thread, one end of which enters a plug 229 fitted into the T 230 in communication with the valve through its hollow stem 187', the other end of which is threaded into stem 187'.

Head elevating and lowering.

The motorized gear reduction unit 31 (Figs. 2, 5, 5a, 5b and 6) for elevating and lowering the head assembly, is fixed to a plate 235 which is secured directly to the top of the turning post 29. A ratchet wheel 236 is keyed to the shaft 237 of this unit, which shaft also carries a bell crank 238 that is free to turn on the shaft. The connecting rod 239 for imparting rocking movement to rocker arm 25 extends between such arm and the short arm of the bell crank. On the long arm of the bell crank is mounted a pawl 241. A spring 242 tends to hold this pawl in engagement with the ratchet wheel, but such engagement is normally prevented by a movable stop 244 pivotally supported on plate 235 and having an arm 245 coupled to the armature 246 of a solenoid 247 by a link 248. A pin 250 carried by the long arm of the bell crank limits the movement of the pawl 241 in the disengaging direction. In order to prevent retrograde movement of the bell crank following the stopping of the rotation thereof on engagement of the pawl arm 241' with latch stop 244, a latch 251 is provided. This latch is pivotally mounted on a post 252, carried by plate 235, and carries a spring 253 which swings the upper end of this latch into engage-

ment with a stop 255 and the lower end into the path of movement of the long arm of the bell crank, which is notched to receive the lower end of this latch.

- 5 When the solenoid 247 becomes energized, its armature 246 is pulled up and the stop 244 operates to release the pawl 241 which is instantly pulled down against the ratchet wheel by its spring. The ratchet wheel, which is constantly 10 rotating, thereafter carries the pawl and crank with it, as illustrated in Fig. 5b. Before the pawl and bell crank have traveled one revolution, the energizing circuit for the solenoid is opened so that its armature again allows the stop 244 to move into the path of the pawl which is accordingly brought to a positive stop upon completion of one revolution. The bell crank, of course, is prevented from backing up under the spring action of the pawl by the swinging of latch 251 into the notched end of the bell crank arm just before it is stopped by engagement of the pawl with stop 244. Thus it will be understood that each time the solenoid is energized the bell crank makes one 15 complete revolution and through connecting rod 239 and rocker arm 25 imparts the hereinbefore described elevating and lowering movement to the gathering head assembly.

Mold carrier and actuating assembly

- 20 The mold equipment of the machine (Figs. 7-11) comprises mold halves 318 and 319, mounted on carriers 320 and 321 by means of suitable adapter plates 322 (Figs. 7 and 8). These carriers have slides 320' and 321' secured thereto 25 resting on side rails 323 mounted on a carrier frame 325. Secured to opposite sides of the slide rails are baffle plates 326 which shield the slide rails from water and glass particles. Attached to the under side of carriers 320 and 321 are gear racks 330 and 331 which engage with a pinion gear 332 mounted in suitable bearings (not shown) pressed into the carrier frame 325 and a cooperating cover 333. Rack 330 is the driving or operating rack and carries on the underside 30 thereof a plate 335 (Fig. 8) having a depending post 336 which carries one end of a connecting rod 337 (Figs. 8, 10 and 11) the other end of which is connected to a bell crank 377 of a mold opening and closing assembly generally designated 341. This assembly, by imparting back and forth movement to rack 330, transmits such movement through pinion gear 332 to rack 331 in the opposite direction, thereby effecting opening and closing movements of the two mold halves. 35 Attached to the outer end of rack 331 is a cross arm 342 carrying adjustable bumper screws, one of which operates the blow control switch 189 and the other of which operates a plunger control switch 212, hereinafter referred to.
- 40 The mold opening and closing assembly includes a drive motor 38 and an associated gear reduction unit 376. Free to rotate on a shaft of this unit is the previously referred to bell crank 377. This bell crank is provided with a pawl 380 (Figs. 65 10 and 11) which, under the influence of a spring 381, is brought into engagement with a constantly revolving ratchet wheel 382, carried by the shaft of the reduction unit, when an opening or closing movement of the mold halves is to be effected. 45 The pawl 380 is at other times prevented from engaging the ratchet wheel by one or the other of two movable stops 386 and 387 arranged 180° apart on a fixed plate 388 mounted on the gear reduction unit, and one of two associated spring biased latches 389 adapted to prevent retrograde 50
- 70

movement of the bell crank as would otherwise be possible when the pawl 380 clears the ratchet wheel. The movable stops 386 and 387 are linked to armatures 391 and 392 (Fig. 11) of solenoids 393 and 394. When a movable stop, for example, stop 386, is engaged by the arm 380' of the pawl 380 and the associated solenoid 394 becomes energized, the stop is withdrawn from the path of movement of the pawl permitting it to engage the rotating ratchet wheel 382. The bell crank is accordingly rotated. As 180° rotation is being completed the bell crank slides past the other latch 389 and pawl arm 380' engages the other movable stop 387 which disengages the pawl from the ratchet wheel. A pin 385 (Fig. 10) pressed into the bell crank is engaged by the pawl just after the pawl clears the ratchet wheel and prevents over-travel of the bell crank. It is substantially at this time that the associated latch 389 drops back of the bell crank to prevent its possible retrograde movement. Thus the bell crank is made to come to rest at two definite positions corresponding to the opened and closed positions of the mold and is held there until solenoid 393 is energized at the proper moment of the machine cycle.

Ware and mold cooling

Ware cooling equipment is provided and comprises two air nozzles 343 (Fig. 9) mounted on diagonally opposite corners of the mold carrier frame, and clamped in plates 344 that swivel on posts 349 which are made adjustable in order to take care of different size ware. These air nozzles by action of springs 357 are made to bear against guiding plates 358, fastened to each mold half, and are connected to a suitable air supply line (not shown) by flexible tubing.

The mold halves are cooled by water ejected from a nozzle 367 (Fig. 9a) connected to a pipe 368 communicating with a water line 370 through a flexible hose. The pipe 368 is supported on one arm of a bell crank 371, the other arm of which is connected to the turning post 29 by a link 344 (Figs. 2 and 9b) so that after the mold halves are separated and as the turning post is rotated to swing the gathering head assembly toward the forehearth, it swings the nozzle between the mold halves. As will be more fully described later, a valve 378 (Figs. 16 and 17) controls the water supply to nozzle 367.

Swing mechanism

As has been previously explained, the gathering head assembly, after gathering a charge of glass, is conveyed by rotation of the turning post 29 to a position over the mold assembly and subsequently returned to the gathering position. These movements are brought about by swing mechanism which includes a motorized gear reduction unit 401 (Figs. 1, 18 and 19) secured directly to the carriage 11 (Fig. 1). A ratchet wheel 402 is keyed to a shaft 403 which extends entirely through the reduction unit. Adjacent the ratchet wheel 402 a bell crank 404 is mounted for free rotation on the shaft. An arm of this bell crank is provided with a crank pin 409 which carries a connecting rod 405 (Figs. 1, 2, 18 and 19) the other end of which connects with a sector gear 408 (Fig. 1) pivoted to a post 407 mounted on the carriage 11 and in mesh with a similar gear 408 secured to the lower end of the turning post 29. The arrangement is such that for each one-half revolution of the bell crank, post 29

is rotated through an arc of approximately 90°. The bell crank is driven by the ratchet wheel 402 through a pawl 410 carried by the bell crank and under the influence of a spring 411. A tripping mechanism for the pawl is mounted on a plate 412 secured to the reduction unit. This mechanism includes a bracket 413 (Fig. 19) bolted to the plate and supporting a swing solenoid 414. The armature 415 of this solenoid is linked to one arm of a trigger 417, the other arm 417' of which passes through an aperture in a tie bar 420 extending between two pawl latches 421 and 422 mounted on plate 412 and located 180° apart. Stops 423 also carried by this plate are provided to limit the travel of the latches. A spring 416 extending between the tie bar and plate 412 holds the latch 422 in inoperative relation with respect to the pawl 410 and latch 421 in operative relation therewith so long as the solenoid 414 remains deenergized. The operating circuit of the swing solenoid is under control of switch 508 of the timing mechanism, hereinafter described. With the swing solenoid 414 deenergized, the gathering head assembly is positioned over the mold assembly. When the solenoid becomes energized its armature 415 actuates trigger 417, thereby withdrawing the latch 421 from engagement with the pawl and moving latch 422 into the path of movement thereof. As the pawl is released, it engages with the ratchet wheel which immediately rotates the pawl and bell crank with it for 180°, whereupon the pawl strikes the latch 422. This disengages the pawl from the ratchet wheel and stops it and the bell crank with the connecting rod 405 in such position that the gathering head assembly has been moved to the gathering station, where it remains until such time that the solenoid 414 again becomes deenergized. When this occurs the pawl will again be allowed to engage the ratchet wheel and will accordingly be rotated 180° to the starting position where the pawl is again disengaged from the ratchet wheel and brought to a stop in its initial position with the gathering head assembly at the molding position.

The lower end of shaft 403 of the motorized gear reduction unit 401 carries a pulley 425 (Fig. 2) for imparting rotary movement to the blow-head spindle 35 during such time that the spindle is at the molding station. The drive is effected through a belt 426, a pulley 427 (Fig. 2a) carried by a stub shaft 424 having a gear 428 at its upper end engaged by a gear 429, on the lower end of a shaft 430 carried by the turning post, just as the gathering head arrives at the molding station. As will be observed from Fig. 2a, the stub shaft 424 is resiliently mounted to permit it to give way if necessary as gear 429 engages it. A pulley 432 on the upper end of shaft 430 imparts rotary movement to the spindle 35 through a belt 433 and pulley 42. Other equipment closely associated with and operated by the turning post comprises a quadrant assembly (Figs. 16 and 17) the functions of which are to actuate the puff control switch 188, a plunger lowering control switch 202 and a head elevating control switch 260. The quadrant also actuates the puff and blow air supply valve 301 as required to supply puff and blow air to the puff and blow valve at the proper times, and, as will more fully be brought out later, opens and closes the supply valve 378 through which cooling fluid is fed to the mold cooling nozzle 367 (Figs. 9 and 9a).

The quadrant

Referring now particularly to Figs. 16, 16a and 17, the quadrant assembly includes a stationary plate 451 arranged alongside the turning post 29 on suitable supports secured to the carriage 11, and a sector 452 secured to the turning post by a support 453 arranged above the stationary plate 451. Sector 452 has mounted on the underside thereof the hereinbefore referred to head elevating and lowering and puff valve solenoid control switches 260 and 188.

Operation of switch 260 during its movement with the turning post in one direction is effected by cams 454 and 455 adjustably mounted on the plate 451, each having an inclined surface 456 over which the roller of switch 260 rides to effect actuation of the switch. The cam 454 is so located that it operates the switch 260 soon after the gathering head leaves the mold position and cam 455 is so located that it operates such switch while the gathering head is completing its swinging movement over the forehearth. A bunter post 460 carried by the sector 452 engages lugs 457 and 458' of the cams 454 and 455 and shifts them out of operative relation to the switch roller to prevent operation of the switch 260 during movement of the gathering head from the forehearth to the molding position. A bunter post 460' located slightly in advance of switch 260 engages surfaces of lugs 457 and 458' to again bring the cams into operative relation with the switch roller during travel of the gathering head toward the forehearth.

Operation of the puff switch 188 is by one or more of a bank of puff control cams 461 mounted for manual movement into and out of the path of movement of the roller of this switch. The number of cams employed depends upon the time period of puff the particular ware being fabricated requires. The drawings illustrate three cams of the bank being employed. The roller of puff switch 188 rides over the cams 461 during movement of the turning post in both directions. The puff operation effected during the movement of the head toward the gathering position is of no utility other than to help keep the air line free of foreign matter.

As the gathering assembly completes its movement from the mold position to the gathering position sector 452 engages the roller of a plunger solenoid control switch 202 which is also mounted on plate 451. From the foregoing it will be understood that the quadrant assembly exercises control over the circuits to the head elevating and lowering solenoid, the puff valve solenoid and the plunger solenoid.

The quadrant sector 452 also actuates the hereinbefore mentioned puff and blow air supply valve 301 and the mold cooling fluid supply valve 378 through the medium of a roller 470 carried on the underside of the sector and adapted to swing forked operating arms 473 and 474 of such valves back and forth between their illustrated full and interrupted line positions. With the valve arm 474 in the position shown in full lines, valve 378 is open so that cooling fluid issues from nozzle 367 (Figs. 9 and 9a), which at this time is in the position shown in Fig. 9, and the mold halves are being effectively cooled. With the valve arm 473 in the position shown in full lines air supply line 204, in connection with the puff and blow valve, is being supplied with high pressure air from puff air supply line 214. Accordingly, as the roller of switch 188 passes leftward over puff

cams 461 as the head leaves its position over a forehearth, a puff of high pressure air is supplied through the puff and blow valve. As the gathering head approaches the mold position the linkage between the post 29 and mold cooling nozzle 367 functions to move the nozzle from between the mold halves to the alternative position indicated by interrupted lines in Fig. 9, arm 474 is shifted to its alternative (closed) position to shut off the water supply from nozzle 367, and arm 473 is shifted to its interrupted line position to shut off the supply of puff air to line 204 and in lieu thereof connect the blow air supply line 209 therewith. At a predetermined time after the swinging movement has been completed, a switch 510 of the timing mechanism closes an operating circuit for the mold halves about the parison. As the mold is closed, the associated blow control switch 189 on the mold carrier (Fig. 7) closes a circuit for the puff and blow solenoid 226 (Fig. 3). Since valve 301 is at this time in the position indicated by interrupted lines, it supplies blow air to the parison to blow it to final form. After blowing has occurred for a predetermined time, a switch 511 of the timing mechanism closes a multiple circuit through the mold opening and atmosphere solenoids 393 (Figs. 10 and 11) and 222 (Fig. 3). The solenoid 222 operates to vent the finished article to atmosphere prior to the opening of the mold. At the beginning of the mold opening movement, switch 189, carried by the crosshead on the mold carrier assembly, opens the circuit of blow solenoid 226 which accordingly closes the puff and blow valve.

As soon as the mold has fully opened, switch 508 of the timing mechanism again closes the circuit of swing solenoid 414 (Figs. 18 and 19), and accordingly the swinging movement of the gathering head from the molding to gathering position proceeds. As the roller of switch 260 (Figs. 16 and 17) passes over cam 454 the circuit of elevator solenoid 247 (Figs. 5 and 6) is again completed thereby causing the described head elevating and lowering cycle to occur for the second time. At this time the gathering head chuck control arm 51 (Figs. 2 and 12) is in its down position, into which position, it will be recalled, it was released by latch 55 of the shearing mechanism to close the chuck jaws about the gathering cup, and latch 106 has freed the rack 103 from its guide 101. As a consequence the rack 103 remains stationary during this cycle of movement of rocker arm 25 and accordingly operation of the shear mechanism does not occur. However, as the gathering head is lowered, the chuck jaws are opened, in the manner hereinbefore described, to release the finished article therefrom. As the head approaches its lowermost position latch 55 (Figs. 3 and 3c) again swings under collar 58 so that during the head elevating portion of the cycle lever 51 (Figs. 2 and 12) is elevated to its initial position away from bumper 54, thereby enabling latch 106 to again lock the shear operating rack 103 in fixed relation to its rack guide 101.

Circuit operation

Referring now to the circuit diagram (Fig. 21), the specific electrical control of the machine and sequence of its operation will be described. For this particular purpose it will be assumed that, to start, the gathering head is in position over the mold, that the mold is open, and branch line 76 switches S1—S9 and main current supply switch

S10 are closed. The switch 508 of the timing mechanism accordingly functions to close the circuit of swing solenoid 414 to effect the swinging movement of the gathering head assembly toward the gathering position. This circuit extends from the main current supply conductor 501 through switch S1, conductor 501', switch S2, solenoid 414, and the contacts of switch 508 to conductor 502. At the beginning of such swinging movement the plunger elevating and lowering solenoid control switch 260 (Figs. 16 and 17), carried by sector 452, engages cam 454 and closes the circuit of the elevator control solenoid 247 (Figs. 5 and 6). This circuit extends from main current supply conductor 501 through switch S1, conductor 501', switches S8 and 260, and the winding of solenoid 247 to the opposite main current supply conductor 502. The elevator solenoid operates its armature to cause the hereinbefore described lowering and elevating movement of the gathering head assembly to be brought about to eject a finished article from the chuck. Upon approach of completion of the swinging movement solenoid control switch 260 (Figs. 16 and 17) engages cam 455 and again closes the circuit of elevator control solenoid 247 to cause the lowering and elevating of the gathering head to be brought about to gather a charge of glass from an associated supply body. As the swinging movement is completed the plunger switch 202 supported by a bracket secured to plate 451 (Figs. 16 and 17) closes the energizing circuit for a relay 213, which circuit extends over conductor 501' through switches S1 and 202, the relay 213 and normally closed breaks contacts of plunger switch 212 on the mold carrier to current supply line 502'. The relay 213, accordingly, becomes energized and at its contacts II completes an obvious locking circuit for itself independently of switches S1 and 202, and at its contacts I closes a point in an operating circuit for plunger solenoid 178, which will be traced later. Following the completion of the swinging movement, gathering cup 40 dips into the supply body, as illustrated in Fig. 20, and lug 211 (Fig. 15) on shear operating rack 115 encounters and actuates lever 187 which in turn actuates vacuum valve 185 to effect suction gathering of a charge into the cup prior to its elevating movement. An atmosphere-after-vacuum switch 509 of the timing mechanism closes its contacts at this time to prepare a circuit for the atmosphere valve solenoid 222 and mold opening solenoid 393. It will be recalled that during the elevating movement of the cup the shear mechanism functions to shear the gather from the supply body and to then recede or advance out of association with cup 40, as illustrated in Figs. 20a-20e, after which the chuck collar is released to effect closure of the chuck jaws; and that during lowering of the chuck collar and closure of the chuck jaws switches 231 and 180 are actuated in close succession. The switch 231 completes the circuit prepared for the atmosphere and mold opening solenoids 222 and 393 respectively. This circuit extends from conductor 501' through switch S4 to point 505 where the circuit divides one branch extending through the mold opening solenoid 393 to point 506 and the other branch extending through the atmosphere solenoid 222, switch 231 to point 506 from which point the common circuit extends through switch 509 to conductor 502. These solenoids, accordingly, both become energized. The operation of the armature of solenoid 393 is without utility at this time

since the mold is already open. The operation of the armature of solenoid 222, however, connects the gathering cup with atmosphere so that there will be no interference with the proper operation of the plunger 165 and at the same time trips the vacuum valve closed. Switch 509 of the timing mechanism opens immediately thereafter, thus causing atmosphere valve solenoid 222 to become deenergized to restore valve 186.

The closure of switch 180 completes the circuit for the plunger solenoid 178 prepared by the closure of contacts I of relay 213. This circuit extends from conductor 501', closed contacts I of relay 213, contacts of switch 180 and solenoid 178 to conductor 502. Solenoid 178 is accordingly energized and lowers the plunger, thereby pinching a small amount of glass between it and the chuck jaws to assist them in holding the charge, as already described and as illustrated in Fig. 20f. After a slight pause, swing switch 508 of the timing mechanism is opened and deenergization of solenoid 414 is effected to start the swinging movement of the gathering head assembly toward the mold position. At the beginning of the swinging movement the roller of the puff switch 188 rides over the puff cams 481 and accordingly completes a circuit for the puff and blow solenoid 226 extending from conductor 501', through switches S1, S9 and 188, and solenoid 226 to conductor 502. This solenoid accordingly becomes energized and raises the valve stems 187' and 187" of the puff and blow valve to pass puff air to the blank. This operation is followed by the closure of timing contacts 504 which close a circuit for solenoids 222 and 393, similar to that closed for these solenoids by contacts 508, to connect the interior of the blank to atmosphere and thus prevent further expansion of the blank prior to its enclosure within the mold. The contacts 504 are again opened to release solenoid 222 and thus close the parison to atmosphere prior to the application of blowing air to the parison, by means of the striker roller carried by timing device chain 528 and cam wheel 534. As the swinging movement continues roller 470 on the sector 452 (Fig. 17) moves the valve operating arm 478 into the position in which blowing air is supplied to the puff and blow valve. After the swinging movement has been completed, the timing mechanism functions to close the contacts of its mold closing switch 510, thereby completing the circuit for the mold closing solenoid 394. This circuit extends from conductor 501' through switch S5, solenoid 394, and switch 510 to conductor 502. The mold closing operation accordingly occurs in the manner hereinbefore described.

As the mold closing operation is completed the make contacts of the plunger switch 212 are closed, followed by the opening of its break contacts, and the contacts of the blow switch 189 (Figs. 7 and 8) are also closed. The relay 213 accordingly becomes deenergized and opens its contacts at this time, but energization of the plunger solenoid 178 is continued through a circuit closed for it by the make contacts of switch 212. The puff and blow solenoid 226 is now energized over an obvious circuit including the blow switch 189.

After blowing has continued for an appropriate time, switch 511 of the timing mechanism closes a circuit through the mold opening solenoid 393. This circuit extends from conductor 501' through switch S4, solenoid 393 and switch 511 to conductor 502. This solenoid accordingly operates

to effect the opening movement of the mold as hereinbefore described. As the mold starts to open contacts 189 open and break the circuit of solenoid 226 which accordingly restores to cut off the supply of blow air. The atmosphere solenoid valve 222, connected in multiple with solenoid 393, is also energized at this time to remove all pressure from within the finished ware. Also, as the mold opens, the switch 212 opens the circuit of plunger solenoid 178 so as to enable retraction of the plunger to be effected in the manner already described. Thus the cycle is completed.

Switch structures

The switches of the timing mechanism 16, which control the circuits of solenoids 393, 394 and 222, are structurally similar to hereinbefore described switches 180 and 231 carried by the gathering head assembly and have operating cam wheels actuated by tripping rollers carried by chains of the timing mechanism.

The mold closing control switch 510 (Figs. 24 and 26) is of the single cam wheel type designed to close a circuit only momentarily. It includes a wheel support 511 secured to a mounting plate 510 and carrying a six tooth cam wheel 512, the teeth of which under the influence of the timing mechanism are caused to successively bear against a follower 519 to force the contacts of a contact actuating plunger 520 in bridging relation with two terminal posts 530 included in the circuit of the mold closing solenoid 394. As will be evident for each sixth turn of the cam wheel the switch closes its contacts momentarily.

Switches 504, 508, 509 and 511 are of the double cam wheel type and differ from switch 510 only in that their cam wheels are secured to sleeves and those wheels cooperative with cam followers have only three instead of six teeth with the crest of each tooth extending through an arc corresponding to that extending between two adjacent teeth of a six-tooth cam. The wheels of each such switch are successively advanced in steps of one-sixth turn by the timing mechanism. In the case of switch 511 all operations are effected by striker rollers 535 and 535' carried by chain 521 successively cooperative with cam wheel 512, whereas the actuations of switches 504, 508 and 509 are effected by striker rollers associated with the chains assigned to such switches and the cam wheels associated therewith. It follows that on one-sixth turn of the cam wheels of one of such switches the cam follower thereof is brought to rest on top of a tooth so that its contacts are closed and that on a subsequent sixth turn of such wheels the cam follower comes to rest between adjacent teeth allowing the contacts to open.

Timing mechanism

The timing mechanism includes a frame 551 (Figs. 22-24a) provided with a series of chains 521-528 each carrying a roller 535 adapted to encounter and actuate the cam wheels of one of the foregoing switches. In the case of chain 521, a second roller 535' is also provided. These chains are carried on idler sprocket wheels 516 mounted on a shaft 552 and so positioned that striking rollers carried thereby engage cam wheels of the above described switches. Each of the chains 521 to 528 is driven by a sprocket 534 carried by a drive shaft 552 and such sprocket is held in fixed relation thereto between suitable spacers 537 arranged on the shaft 552 between a spacer 537 pinned thereto and suitable clamping

and locking nuts 538. Striker roller 535' on chain 521 actuates cam wheel 512', turning it and its companion switch operating cam wheel 533 one-sixth revolution. Since the crest of each tooth of cam 533 extends through an arc corresponding to that extending between two adjacent teeth of cam wheel 512', it follows that the cam follower of switch 511 is depressed and its contacts held closed by cam wheel 533 until such time that it is turned another sixth of a revolution. The striker roller (not shown) carried by chain 522 (Fig. 24) actuates switch 509 through the medium of its cam wheel 529 to close the contacts of such switch, whereas its contacts are opened by a striker roller (not shown) carried by chain 523 cooperative with a cam wheel 532. The chains associated with switches 504 and 508 operate such switches in a similar fashion. The switch 510, having but a single six tooth wheel, 20 simply has its circuit momentarily closed each time a striker roller carried by the associated chain 528 encounters it.

The timing of the operation of switches 504, 508, 509 and 510 is made adjustable with respect to the time of operation of switch 511 which is fixed and may be said to begin the machine cycle. The latter switch, as previously brought out, controls the opening of the mold and momentarily opens the atmosphere valve to fully relieve pressure in the finished article as the mold opens.

The mechanism by means of which the timing of the operation of switch 504 is made adjustable comprises a bell crank BC1 (Figs. 24 and 24a) provided with a hub freely rotatable about spacer 537' on shaft 552. Arm 540 of this bell crank carries an idler gear 541 in mesh with the upper run of chain 528, whereas arm 542 is adjustably latched to a quadrant Q1. Quadrant Q1 is rigidly attached to and supported by bell crank BC2 by angle iron 544 riveted to bell crank BC2 and fixed to the quadrant by means of a screw 546 passing through an ear 545 integral with the quadrant. By moving arm 542 upward or downward about the quadrant Q1 the idler sprocket 541 is raised or lowered, thereby changing the position of its striker roller 535 with respect to switch 504 and in so doing advancing or retarding the time of the opening operation of this switch with respect to the time of its closing operation. To explain further with the arm 542 in a lowered position, as illustrated in Fig. 22, the slack in chain 528 is below the axes of sprockets 534 and 516 in which position its roller 535 is advanced toward cam wheel 512 (Fig. 24). By raising arm 542, to the position illustrated in Fig. 24a, the slack in chain 528 is transferred to above the axes of sprockets 534 and 516, thereby backing roller 535 away from cam wheel 512. As will be appreciated, idler sprocket 516 being free to turn permits the shifting of the position of the slack portion of chain 528 as above described without the necessity of imparting any turning movement to the drive sprocket 554.

The bell crank BC2 is in similar fashion associated with a chain 527 which carries a roller (not shown) cooperative with a cam wheel 530 to close switch 504. However, since the quadrant Q1 is carried by bell crank BC2, movement of bell crank BC2 in like respect advances or retards both the closing and opening time of switch 504. The quadrant Q2 associated with bell crank BC2 is supported on a bell crank BC4 through the medium of an angle iron 548. The time varying mechanism associated with switch 510 includes

the bell crank BC3 having an associated quadrant Q3 also attached to angle iron 548 and therefore also supported by the bell crank BC4, and is movable independently of bell cranks BC1 and BC2 to modify the time of operation of switch 510.

The bell crank BC4 controls through its idler gear and chain 525 the time of opening of switch 508 in the same manner that such control is exercised by bell crank BC1 over switch 504. Since, however, the quadrants Q2 and Q3 are supported by bell crank BC4, and further, since the quadrant Q1 is supported by bell crank BC2, bell cranks BC1-BC3 will all operate with bell crank BC4 to advance or retard the time of operations under their control. The quadrant Q4 associated with the bell crank BC4 is attached by means of an angle iron 549 to a master bell crank BC5 carrying an idler sprocket associated with chain 524 so as to regulate the timing of closure of switch 508. Linked to the bell crank BC5 are bell cranks BC6 and BC7 having idler gears associated with chains 522 and 523 respectively. It follows, therefore, that by movement of bell crank BC5 all chains 522-528 are shifted to modify the time of operations under their control. The quadrant Q5 is immovable, being secured to the framework of the timing mechanism. It is to be noted that not only can bell crank BC5 be operated to simultaneously advance or retard the time of operations under control of chains 522-528 with respect to those under control of chain 521, but also that bell cranks BC1 and BC3 can be operated to advance or retard the time of operations under control of their chains 528 and 528 with respect to those under control of chains 522-525, and 527, that bell crank BC2 can be operated to in like manner advance or retard the time of operations under control of chains 527 and 528 with respect to the remaining chains, and that bell crank BC4 can in a similar fashion be operated to advance or retard the time of operations under control of chains 525-528.

As clearly shown in Fig. 2, the timing mechanism is driven by a motor 543 through the medium of a suitable chain and a variable speed transmission 550 enabling the ready variation of speed of the timing mechanism and accordingly of the entire glass working machine.

While in the foregoing there has been shown and described the preferred embodiment of the invention, it is to be understood that minor changes in the details of construction and combination of parts may be resorted to without departing from the spirit and scope of the invention as claimed.

I claim:

1. In a glassware forming machine, a glass gathering and blowhead assembly, a self contained power unit for moving said assembly back and forth between gathering and finishing stations, a second self contained power unit for moving said assembly into and out of a pool of glass at the gathering station, means operated during the latter movements of said assembly for gathering and retaining a charge of glass solely by suction, means for isolating the charge from that in the pool, means for thereafter mechanically locking the charge to the assembly, means for introducing air into the charge during its travel toward the finishing station to form a hollow blank, a divided mold assembly at the finishing

station, a third self contained powered unit for opening and closing said mold assembly, a timing mechanism under whose control the time of operation of the respective self contained units are placed, and a separate motor for driving said timing mechanism.

2. In a glassware forming machine a combined gathering and blowhead assembly, means including an electric device for moving said assembly to and fro between gathering and finishing stations, means including a second electric device for moving said head to perform charge gathering, shearing and ware ejecting functions, a divided mold assembly at the finishing station, means including a third electric device for bringing said mold assembly into and out of cooperative relation with gathers of glass delivered to the finishing station from time to time, means for supplying air through the head to the glass when surrounded by the finishing mold, and a separate timing mechanism having switches for controlling said means for the respective purposes set forth.

3. In a glassware machine, a gathering head, means for imparting a lowering movement to said head into a supply body of glass and for then imparting a raising movement to said head to suction gather a charge, a shear mechanism associated with said head operated consequent to its raising movement to shear the gather from the supply body, a chuck assembly carried by said head, and means for tripping said chuck assembly to its closed position immediately after the shear has separated the gather from the supply body to mechanically clamp the gather to said head.

4. In a glassware machine, a gathering head, means for imparting lowering and raising movements to said head to suction gather a charge from a supply body of glass, a shear mechanism associated with said head operated consequent to its raising movement to shear the gathered glass from the supply body, a chuck assembly associated with said head tripped to closed position by said shear mechanism to mechanically clamp the gather to the head, a plunger associated with said head, mechanism for operating said plunger to a position to assist said chuck assembly in holding the gather attached to said gathering head, and plunger mechanism control means actuated during the closing movement of the chuck assembly.

5. In a glassware forming machine, a gathering assembly including a gathering cup having a bottom opening, means for momentarily lowering said cup into contact with a molten supply body and for temporarily establishing communication between said cup and a vacuum line whereby a charge is gathered by suction; shear mechanism, operated while the gather is held solely by suction, to separate the gather from the supply body; mechanism operated at the conclusion of the shearing operation to reduce the cross section of the opening of the cup to hold the charge attached thereto after communication of the cup with the vacuum line has been broken, and means for thereafter breaking communication between the vacuum line and in lieu thereof establishing communication with a supply of air under pressure to force the glass back out through its bottom opening into a hollow parison outside of the gathering cup.

DAVID E. GRAY.
